3-[ACETONYL; HYDROXYETHYL; AND 2-(4-PYRIDYL)-ETHYL]-1-(5-NITROFURFURYLIDENE-AMINO) HYDANTOIN

Julian Getz Michels, Norwich, N.Y., assignor to The Norwich Pharmacal Company, a corporation of New York

No Drawing. Filed Dec. 27, 1960, Ser. No. 78,315
4 Claims. (Cl. 260—240)

This invention relates to 1-(5-nitrofurfurylideneamino)-hydantoins substituted in the 3-position of the hydantoin nucleus which may be represented by the formula:

in which R represents a member of the group consisting of acetyl, hydroxyethyl and 2-(4-pyridyl)ethyl. 20

These hydantoins are highly effective, relatively non-toxic systemic antimicrobial agents. They control systemic infections in animals caused by microorganisms such as *Staphylococcus aureus* and *Eimeria tenella*. Mice lethally infected with *S. aureus* are protected by the peroral administration of a single dose of from 105-210 mg./kg. of these compounds given post infection as a suspension in carboxylmethylcellulose. Chickens infected with *E. tenella* are protected against the morbidity and mortality associated with coccidiosis provoked by that organism through the administration of these compounds incorporated in their feed at a level of 0.022% by weight.

The dose of these compounds required to achieve therapeutic response is considerably less than that eliciting any unwanted toxic effect. In mice tolerable doses of these compounds range from 770-2200 mg./kg. In chickens no evidence of toxic side effect is seen at the level employed to combat coccidiosis.

I have found that the 3-[acetyl; hydroxyethyl; and 2-(4-pyridyl)-ethyl]-1-(5-nitrofurfurylideneamino)hydantoins which I have invented can be prepared using materials which are readily available in the art. In general the methods which I have employed for the production of these compounds involve reacting a 1-(alkylideneamino)hydantoin or a salt thereof with a compound containing a functional unit to introduce the substituent above defined as R and treating the formed 3-R-substituted-1-(alkylideneamino)hydantoin under hydrolytic conditions if necessary to free the 3-R-substituted-1-amino-hydantoin for reaction with 5-nitro-2-furaldehyde or a derivative thereof hydrolyzable thereto.

The method which I currently prefer to make the compounds of my invention is dictated largely by the nature of the functional unit in the compound employed for the introduction of the 3-R-substituent. When said functional unit is a halogen atom, such as chlorine, I have found the use of a salt of a 1-(alkylideneamino)hydantoin, for instance the sodium salt, in the presence of an inert reaction medium composed of an organic solvent such as pyridine or dimethylformamide and the application of heat to the reaction mixture to be advantageous and desirable for the production of the 3-substituted-1-(alkylideneamino)hydantoin in good yield. A representative schema is:

I.

2

When said functional unit is a vinyl group, I have found that the salt form of a 1-(alkylideneamino)hydantoin is unnecessary and that the reaction proceeds readily and in good yield in the presence of a solvent and under the influence of heat. A representative schema is:

II.

In order to convert the 3-substituted-1-(alkylideneamino) hydantoins depicted in the above representative schema (I and II) to the desired 5-nitro furfurylidene compound, I have found it to be advantageous to hydrolyze them in an acidified aqueous medium such as aqueous mineral acid under the influence of heat and to add 5-nitrofuraldehyde or an equivalent thereof, such as 5-nitrofuraldehyde diacetate which is readily hydrolyzed under the reaction conditions, to the medium. Where the alkylidene component is volatile, steam distillation in the presence of acid is an effective means for removing the volatile component from the reaction mixture and at the same time effecting hydrolysis.

The compounding of the 3-substituted-1-(5-nitrofurylideneamino) hydantoins of my invention in dosage form is readily carried out in accordance with the pharmaceutical art. Tablets, suspensions, elixirs, and the like can be prepared using as carriers excipients and adjuvants common to the art.

In order that my invention may be available to and understood by those skilled in the art the following illustrative examples are supplied:

EXAMPLE I

3-[2-(4-Pyridyl)Ethyl]-1-(5-Nitrofurfurylideneamino) Hydantoin

A mixture of 157 g. (0.77 mole) of a 1-benzylidene-aminohydantoin, 500 cc. of pyridine and 90 g. (0.86 mole) of 4-vinylpyridine is refluxed for 30 hours then poured into 3.5 l. of water. The solid that forms is filtered, washed with water and dried at 110°. There is obtained 203 g. (85%) of the intermediate compound. This product is steam distilled with a mixture of 300 cc. water and 80 cc. sulfuric acid to remove the benzaldehyde. The solution is filtered through infusorial earth to clarify and then treated with an alcoholic solution of 100 g. (0.7 mole) of 5-nitro-2-furaldehyde. A small amount of nitrofurantoin that forms is removed by filtration and the filtrate extracted with ether to remove any excess 5-nitro-2-furaldehyde. The resulting raffinate is basified with ammonia to precipitate the crude 1-(5-nitrofurfurylideneamino)-3-[2-(4-pyridyl)ethyl]hydantoin. After filtering, washing with water, alcohol and ether, and air-drying, this material weighs 158 g. (70%). It is purified by re-dissolving in dilute hydrochloric acid, treating with charcoal and reprecipitating. A recovery of 87.5% is obtained. Recrystallization from 1:1 nitromethane:

methanol (10 cc./1 g.) using charcoal gives purified 3-[2-(4-pyridyl)ethyl]-1-(5-nitrofurfurylideneamino)hydantoin decomposing at 210-212°.

In place of 5-nitro-2-furaldehyde, 5-nitro-2-furaldehyde diacetate may be used accompanied by heating to effect its hydrolysis.

EXAMPLE II

3-(2-Hydroxyethyl)-1-(5-Nitrofurfurylideneamino) Hydantoin

To a solution of 10.2 g. (0.05 mole) of 1-benzylideneaminohydantoin in 250 cc. of dimethylformamide is added 2.2 g. of 55% sodium hydride in mineral oil. When the sodium hydride has dissolved, 6.2 g. (0.0506 mole) of chloroethyl acetate (JACS 46:766 (1924)) is added. The mixture is heated at 110-120° overnight, then cooled. After filtering the salt, the dimethylformamide is removed under reduced pressure. The residue is steam distilled in the presence of dilute sulfuric acid until the solid dissolves. The aqueous solution is treated with charcoal, filtered and reacted with 7 g. of 5-nitro-2-furaldehyde in alcohol. After cooling, the yellow precipitate is filtered, washed with water, alcohol and ether and dried at 110°. There is obtained 11.5 g. (81.5%) of 3-(2-hydroxyethyl)-1-(5-nitrofurfurylideneamino) hydantoin decomposing at about 233°. Recrystallization from nitromethane using charcoal raised the decomposition point to 236-238°.

For 5-nitro-2-furaldehyde its diacetate may be substituted.

EXAMPLE III

3-Acetonyl-1-(5-Nitrofurfurylideneamino)Hydantoin

A mixture of 40 g. (0.15 mole) of sodium nitrofuran-35 toin, which may be prepared by treating a suspension of

nitrofuran-35 toin in anhydrous alcohol with sodium methoxide, 500 cc. of dimethylformamide and 15 cc. chloroacetone is heated on the steam bath for 2 1/4 hours, then the dimethylformamide is distilled off under reduced pressure. The residue is triturated with water, filtered, washed with water, alcohol and ether and dried. There is obtained 35.5 g. (81% crude) of 3-acetonyl-1-(5-nitrofurfurylideneamino)hydantoin. Recrystallization from 175 cc. nitromethane using charcoal gives 29.4 g. (83% recovery) of purified product melting at 230-233°.

What I claim is:

1. A compound having chemotherapeutic activity upon oral administration and represented by the formula:

20 in which R represents a member of the group consisting of acetonyl, hydroxyethyl and 2-(4-pyridyl)ethyl.

2. 3-[2-(4-pyridyl)ethyl]-1-(5-nitrofurfurylideneamino)-hydantoin.

3. 3-(2-hydroxyethyl)-1-(5-nitrofurfurylideneamino)-hydantoin.

25 4. 3-acetonyl-1-(5-nitrofurfurylideneamino)hydantoin.

5. 3-(2-hydroxyethyl)-1-(5-nitrofurfurylideneamino)hydantoin.

UNITED STATES PATENT OFFICE
CERTIFICATE OF CORRECTION

Patent No. 3,097,202

July 9, 1963

Julian Getz Michels

It is hereby certified that error appears in the above numbered patent requiring correction and that the said Letters Patent should read as corrected below.

Column 1, line 29, for "carboxymethylcellulose" read
--carboxymethylcellulose --; column 2, lines 1 to 7, the
formula should appear as shown below instead of as in the
patent:

column 2, line 52, after "of", second occurrence, strike out
-- a --.

Signed and sealed this 21st day of January 1964.
